CLAIM

The ornamental design for a wall mounted cosmetic cabinet, as shown and described.

DESCRIPTION

FIG. 1 is a perspective view of a wall mounted cosmetic cabinet showing my new design;

FIG. 2 is a front elevational view thereof;

FIG. 3 is a top plan view thereof;

FIG. 4 is a bottom plan view thereof; and

FIG. 5 is a left end elevational view, the right end being identical thereof.

The rear elevational view of the wall mounted cosmetic cabinet is conventional in appearance.
